UNITED STATES PATENT OFFICE.

GEORGE M. KNEUPER, OF NEW YORK, N. Y.

FILTER.

No. 817,252.

Specification of Letters Patent. Patented April 10, 1906.

Application filed August 12, 1904. Serial No. 220,450.

To all whom it may concern:

Be it known that I, GEORGE M. KNEUPER, a citizen of the United States, and a resident of the borough of Manhattan, city, county, 5 and State of New York, have invented certain new and useful Improvements in Filters, of which the following is a specification.

My invention relates to the manufacture of filters, and has for its object to provide a 10 very efficient and durable filter of considerable lightness.

The invention will be fully described hereinafter, and the features of novelty pointed out in the appended claim.

Reference is to be had to the accompanying drawings, in which—

Figure 1 is a sectional elevation of an apparatus for making filters according to my invention, showing said apparatus at the initial 20 stage of the operation. Fig. 2 is a similar view showing the apparatus at the final stage of the operation. Fig. 3 is a sectional plan on line 3 3 of Fig. 1. Fig. 4 is a longitudinal section of the form of filter made with the apparatus shown in Figs. 1, 2, and 3. Fig. 5 is a sectional elevation of another form of filter-making apparatus constructed according 25 to my invention. Fig. 6 is a sectional elevation of still another apparatus embodying my 30 invention, and Fig. 7 is a sectional plan taken on line 7 7 of Fig. 6.

In making my improved filter I employ a vessel having a perforated wall, so that liquid may pass therethrough, and adjacent to this 35 perforated wall I locate an expansible body adapted to be forced toward said wall. If the vessel is filled with paper-pulp suspended in water, and if then the expansible body is distended or blown up quickly, the water will 40 be forced through the perforated wall; but the pulp will remain compressed between the expansible body and the perforated wall and will form a continuous sheet or lining against said wall.

45 In detail the apparatus and procedure may be as follows:

In Figs. 1, 2, and 3 A indicates the operative inner wall of the apparatus, which may be cylindrical and may consist of perforated 50 sheet metal or of wire-netting. B indicates a pouch of suitable porous or pervious material, such as canton-flannel, the upper edge of said pouch being folded over the outer wall C, which, as shown, may consist of two connected wire screens of cylindrical shape. 55 The outer wall C is secured to a bottom D,

which may be solid or perforated and which is preferably provided with legs D', so that the entire receptacle may be conveniently set within a tank E or the like. Within the perforated wall A is arranged an expansible body F, for which I generally employ a rubber bag. This bag extends substantially the entire length or height of the receptacle and is secured at its top to a cover G. This 65 cover may be provided with a filling-opening closed by a plug G' and is normally held down against a flange A' at the top of the inner wall A by means of a nut H, which screws upon a perforated tube I, extending 70 through the cover G and within the receptacle. The upper end of the bag F is secured to said tube I. The lower end of the tube may be free within the receptacle, or, if preferred, the lower end of the tube may, as 75 shown, be passed through the rubber bag and through the bottom B, being there secured by a nut I'. A strengthening-flange C' is preferably located at the upper end of the outer wall. 80

In operation the apparatus above described is placed in the tank, which is either empty or filled with water. Pulp suspended in water is poured into the central chamber J. Then air is blown into the tube I, so as to 85 issue through the perforations thereof into the bag F. By the application of suitable pressure the bag is quickly expanded against the inner wall A into substantially the form shown in Fig. 2. The water is quickly driven 90 out through the perforated walls A and C and the pervious pouch B; but the pulp is retained against the inner surface of the inner wall A and forms a continuous compressed lining thereon. The pressure will of course 95 cause the pulp lining to conform closely to the meshes of the wall A, and the said wall and its pulp lining will therefore be securely connected, so as to render them available for use as one structure. However, the lining 100 may be separated from the wall A and used alone, if desired. After forming the lining on the inner wall, as described, the receptacle is removed from the tank.

The compressed-pulp lining K, produced 105 on the perforated wall A, constitutes an efficient filter either alone or together with said wall as a carrying-frame. This filter, Fig. 4, may be removed from the apparatus by unscrewing nut H, lifting off the cover G, taking 110 hold of the flange A' at the top of the inner wall, and lifting the inner wall, together with

the compressed-pulp lining K, from the receptacle. This inner wall with the compressed lining thereon may then be used as a filter in any suitable apparatus. It will be seen that one face of the lining engages the perforated wall A, the other face being freely exposed, so that the lining is allowed to expand in one direction in case it should swell in use. I consider it preferable when using the filter to have the liquid pass in through the exposed inner surface of the lining and out through the meshes of the perforated wall. Another inner wall of like construction is then put in the receptacle and a filter-lining is formed thereon in the same manner as above described, and thus the apparatus may be used for producing a great number of filters. It will of course be understood that after the receptacle has been removed from the tank and before the inner wall is removed the rubber bag should be deflated. The pouch B is not absolutely necessary, but prevents the fibers from passing to and through the outer wall C when the perforations of the inner wall are beyond a certain size. The pouch B thus insures an easy separation of the inner wall A from the other parts of the apparatus after the pulp lining K has been made. If the meshes of the inner wall are sufficiently close, the pouch B, and even the outer wall C, may be dispensed with. In any event, however, the top or cover G should be securely connected with the bottom D, so as to prevent any leakage at the edges of the inner wall A. A rubber gasket G² may be applied to the cover, so as to engage the flange A'. In order to provide a receptacle for the water expelled by the inflation of the bag F without unduly increasing the height of the tank E, the latter may be made with a stand-pipe E' extending upwardly beyond the cover G.

It will be obvious that in the operation above described an opening K' will be produced at the bottom of the filter-lining K. (See Fig. 4.) In cases where it is desired to produce a filter having a closed bottom the pipe 12 would terminate above the bottom D² of the receptacle and within the bag F', Fig. 5. In this case the cover G² could be lifted with the pipe I² and bag F' after the production of the filter, and then the bottom of the lining would be closed entirely by the end portion. As in this case the pipe I² does not extend through the bottom D², other means than those used in Figs. 1, 2, and 3 must be provided for holding the cover G² down. For instance, screw-rods L may be hinged to the bottom D² and fitted into slotted ears G⁴ of the cover, the tension being produced by means of winged nuts M.

In Figs. 6 and 7 the inner wall a is formed by rolling a sheet of wire-gauze or the like into cylindrical form, so that there will be two or more layers at certain points, and this cylinder is then held in shape in any suitable

manner, as by end rings a', L-shaped in cross-section and adapted to engage gaskets d' g², located on the bottom d and cover g, respectively. The bottom d is shown integral with a cylindrical imperforate outer wall e. This wall may be provided with a stand-pipe e' corresponding in function to the stand-pipe E'. A plug g' normally closes an opening in the cover g, through which the chamber j may be filled with pulp suspended in water. This chamber also contains the expansible body f, fitted on the pipe i, through which air or other suitable medium may be blown or forced into the bag f to expand the same. Nuts h i' hold the parts of the apparatus together. The operation is exactly the same as with the form of construction first described, with the additional advantage that the pulp lining may be stripped much more readily from the perforated wall upon which it is formed, so that such lining may be taken off and applied to other carriers. The cleaning of the perforated wall is also much facilitated by this construction.

While I have described the production of a compressed-pulp lining forming a filter on the inner surface of the inner wall, I desire it to be understood that my invention is not restricted to the particular construction illustrated.

In all the forms of apparatus herein shown it obviously is easy to substitute perforated walls A a of different diameters for those shown in the drawings, so that the same apparatus may be used for making filters of different sizes.

Instead of pulp I may employ any other substance capable of suspension in water or other liquid and of separation from said liquid by forcing the liquid through a perforated wall. If such substance is porous, the resulting sheet or lining can be used for filtering purposes. In all events a lining will be produced which conforms to the shape of the wall, so that my invention, considered broadly, provides means for molding articles of various kinds quickly and without requiring the application of heat.

Various modifications may be made without departing from the nature of my invention.

I claim as my invention—

A filter consisting of a cylindrical relatively rigid wall having perforations, and a cylindrical lining of compressed pulp applied to said wall and provided with a pulp bottom integral with the pulp-cylinder.

In testimony whereof I have hereunto set my hand in the presence of two subscribing witnesses.

GEORGE M. KNEUPER.
